Primary Examiner—Alan P. Douglas*Assistant Examiner*—Gary D. Watson*Attorney, Agent, or Firm*—Grace J. Fishel[57] **CLAIM**

The ornamental design for a sports seat, as shown.

DESCRIPTION

FIG. 1 is a perspective view of a sports seat showing my new design in use in a canoe;

FIG. 2 is a perspective view of my new design in use as a beach chair;

FIG. 3 is a front elevational view thereof;

FIG. 4 is a left side elevational view thereof;

FIG. 5 is a top plan view thereof;

FIG. 6 is a rear elevational view thereof; and,

FIG. 7 is a bottom plan view thereof.

The canoe and man shown in broken lines in FIGS. 1 and 2 and the seat and backrest shown in FIGS. 1-7 denote the nature and environmental use of the design and are not part of the design.

FIG. 3

FIG. 4

FIG. 5

FIG. 6

FIG. 7
